UNITED STATES PATENT OFFICE.

JOSEPH F. PUNZAK, OF BROOKLYN, NEW YORK, ASSIGNEE TO DAVID H. ZELL, INC.,
OF NEW YORK, N. Y., A CORPORATION OF NEW YORK.

COIN BANK.

Application filed March 3, 1924. Serial No. 696,450.

To all whom it may concern:

Be it known that I, JOSEPH F. PUNZAK, a citizen of the United States, and a resident of Brooklyn, county of Kings, and State of New York, have invented certain new and useful Improvements in Coin Banks, of which the following is a specification.

This invention relates to coin banks and has for its primary object to provide a novel form of bank which is simply constructed from stamped and pressed sheet metal plates and in which the coins will be always visible so that the amount contained in the bank can be ascertained at a glance.

In one embodiment of the invention, I provide three sheet metal plates held together in assembled relation by a marginal clamping rim and said plates having coinciding slots of S-shaped form and the opposite side plates being pressed to provide a coin-way at each side of the intermediate plate and said outer plates having portions providing parallel bars intersecting said slots and thus producing a representation of the conventional dollar sign. It is one of the important features of the invention to provide a simple and effective latch means closing the coin-ways at one of their ends to prevent the extraction of the coins except by the use of a suitable key.

It is a further general object of the invention to provide a coin bank of the above character capable of holding a large number of coins and which is of such size and shape that it may be conveniently carried in the pocket said bank consisting of few simply constructed elements so that the device can be produced at comparatively small manufacturing cost.

With the above and other objects in view, the invention consists in the improved coin bank and in the form, construction and relative arrangement of its several parts as will be hereinafter more fully described, illustrated in the accompanying drawing and subsequently incorporated in the subjoined claims.

In the drawing wherein I have shown one simple and satisfactory embodiment of the invention and in which similar reference characters designate corresponding parts throughout the several views:

Figure 1 is a side elevation of a coin bank embodying my present improvements;

Figure 2 is a vertical edge view thereof; 55
Figure 3 is a section taken on the line 3—3 of Figure 1;

Figure 4 is an end elevation;

Figure 5 is an enlarged detail section illustrating the latch device for the coin-way closure; 60

Figure 6 is a sectional view taken on the line 6—6 of Figure 5;

Figure 7 is a detail view illustrating the guard device at the entrances to the coin-ways; and 65

Figure 8 is a horizontal section taken on the line 8—8 of Figure 7.

For purposes of illustration, I have shown the bank as of general rectangular form and 70 consisting of an intermediate plate 5 and the side plates 6 and 7 respectively. These body plates of the bank are of sheet metal of the requisite gauge. The intermediate plate 5 has an S-shaped slot 8 cut therein 75 and the side plates 6 and 7 are provided with similar slots 9 and 10 respectively, said slots, however, being intersected by parallel portions of the plate forming bars 11 so that said slots and bars in the outer side plates 80 represent the conventional dollar sign. The several plates 5, 6 and 7 are thus formed by suitable stamping operations and said side plates in spaced relation to the slots therein and concentric with the inner and outer 85 edges of said slots, are inwardly flanged as at 12 to engage against opposite sides of the intermediate plate 5 whereby the several plates are spaced apart as seen in Figure 3 of the drawing, thus producing the coin-ways 13. The marginal edges of the plates 5, 6 and 7 are secured together by sheet metal clamping rims 14 which embrace such edge portions of the plates and are securely clinched or otherwise permanently secured to 90 the outside plates 6 and 7. One of the clamping rims 14 along one of the longitudinal side edges of the structure does not extend the full length thereof but terminates at a point in spaced relation to one end of the 100 coin-ways 13 for a purpose which will be presently explained.

The other ends of the coin-ways 13 open through the other marginal rim 14 on the opposite longitudinal edge of the bank, and to the edge of the intermediate plate 5 at this end of the coin-ways a U-shaped metal guard member 15 is applied. This guard 105

member is formed of resilient sheet metal and has a plurality of spring fingers 16 at each of its ends which normally extend obliquely across the respective coin-ways. 5 Thus it will be understood that when a coin is inserted into either of the coin-ways 13, as indicated in Figure 1, the spring fingers 16 will be forced against the intermediate plate 5 by the pressure of the coin and after 10 the coin has passed said fingers, the latter will resume their normal positions, thus preventing the extraction of the coin from said coin-ways. This guard member 15 is held in position upon the edge of the plate 5 by 15 the part of the marginal rim 14 between the openings in said rim which communicate with the coin-ways.

The other ends of the coin-ways 13 are normally closed by a U-shaped metal strip 20, 17, said strip at one of its ends having the side portions thereof laterally extended to form ears 18 which are pivotally engaged upon a pin 19 extending transversely through the body plates 5, 6 and 7. In the 25 free end of the U-shaped strip 17 a latch dog 20 is pivotally mounted upon the pin 21, said dog having a long arm 22 provided with a shoulder 23 in one edge thereof. This dog is also provided with a second relatively short arm 24 extending at right angles to the arm 22 and within the channel of the strip 17. To this arm 24 one end of a leaf spring 25 is fixed. The edges of the metal plates 5, 6 and 7 are cut away as at 26 to 30 accommodate the spring 25 and the intermediate plate 5 also has its corner portion cut away as at 27 to accommodate the latch dog 20. Between the side plates 6 and 7 a keeper lug 28 is fixed and has an inclined 35 face 29 over which the arm 22 of the dog is adapted to ride when the closure strip 17 is moved to its closed position. In spaced relation to this keeper lug the marginal strip 14 is provided with an opening 30 through which a suitable key or pin, indicated at 31, may be inserted to engage the end 40 of the arm 22 and disengage the same from the keeper lug 28.

From the above, it will be seen that when 50 the closure 17 is moved from the dotted line position seen in Figure 5, to the full line position, the arm 22 of the dog 20 will ride over the inclined surface of the lug 28 until the shoulder 23 on said arm engages behind 55 said lug. In this rocking movement of the dog 20, the free end of the spring 25 bears against the base wall of the channel of the strip 17, whereby the arm 22 is yieldingly urged upon the keeper lug 28. When the 60 pin or key 31 is inserted and the end of the arm 22 presses inwardly, the spring 25 will be placed under additional tension so that as soon as the shoulder 23 is disengaged from the end of the lug 28, the reaction of the 65 spring 25 forcibly impels or projects the

pivoted closure 17 to its open position, thereby exposing the ends of the coin-ways so that the coins may be readily extracted. This removal of the coins is easily accomplished by engaging the fingers with the 70 coins through the slots 9 and 10 in the side plates or by manipulating the bank so that the coins will roll by gravity in the coin-ways and finally drop from the open ends thereof. After the coins have been removed, 75 the closure member 17 is again moved to position to cover the open ends of the coin-ways and is automatically latched in such position by the pivoted dog 20 in the manner above explained. 80

From the foregoing description considered in connection with the accompanying drawing, the construction and manner of operation of the device will be clearly understood. It will be seen that I have produced a very novel form of coin bank which is capable of holding a comparatively large number of coins, and is of such dimensions that it can be conveniently carried in the pocket. In the construction illustrated, the bank is designed to receive ten dimes in each of the coin-ways 13 so that a total of two dollars can be collected therein before it is necessary to open the bank and remove the accumulated coins. Of course, it is apparent that the device might be made in other sizes for the purpose of receiving coins of other denominations, and additional intermediate plates may be used to provide a greater number of the coin-ways. A bank of the construction described may be very cheaply manufactured for distribution by banking institutions to its depositors for the collection of small coins to be periodically deposited upon savings accounts. 100

I have above described a form of the latch means for the coin-way closure which has been found very satisfactory in practical use. It is however, to be understood that this as well as the other structural features of the device are susceptible of embodiment in other alternative structures and I accordingly reserve the privilege of resorting to all such legitimate changes in the form, proportion and relative arrangement of the several parts as may be fairly embodied within the spirit and scope of the invention as claimed. 110

I claim:

1. A coin bank having intermediate and side plates provided with spaced portions forming coin-ways opening at their ends upon opposite side edges and adjacent to opposite ends of the bank, means securing said plates together at their marginal edges, guard means at the entrance ends to said coin-ways through the side edges adjacent to one end of the bank, a pivoted closure for the other ends of said coin-ways through the other side edge adjacent to the 120

other end of the bank, and latch means to hold said closure in effective position preventing the removal of the coins.

2. A coin bank comprising intermediate and side plates having portions spaced apart to provide parallel coin-ways opening at their ends upon opposite side edges and adjacent to opposite ends of the bank, means securing said plates together at their marginal edges, a guard having resilient guard fingers extending inwardly and across each coin-way at the entrance and through the side edges adjacent to one end of the bank, a pivoted closure for the other ends of said coin-ways through the other side edge adjacent to the other end of the bank, and key-actuated latch means for said closure.

3. A coin bank comprising intermediate and side plates having portions spaced apart to provide parallel coin-ways opening at their ends upon opposite side edges of

the bank, means securing said plates together at their marginal edges, a guard having resilient guard fingers extending inwardly and across each coin-way, a pivoted latch dog carried by said closure, a leaf spring fixed to one end of said dog and bearing at its free end against the closure, a keeper lug with which said dog is adapted to coat as the closure is moved to position over the ends of the coin-ways while said spring is placed under tension, said dog having a shoulder engaging over one end of the keeper lug, said dog adapted to be actuated by a suitable key to disengage said dog from the keeper lug and permit said spring to move the closure to its open position.

In testimony that I claim the foregoing as my invention, I have signed my name hereto.

JOSEPH F. PUNZAK.
